UNITED STATES PATENT OFFICE.

HARRY A. MILLER AND FRANK M. ADAMSON, OF PASADENA, CALIFORNIA, ASSIGNEES OF FORTY ONE-HUNDREDTHS TO FRANK P. HARRIS, OF PASADENA, CALIFORNIA, AND FORTY ONE-HUNDREDTHS TO A. T. HAY AND TWENTY ONE-HUNDREDTHS TO HARRY A. MILLER, OF LOS ANGELES, CALIFORNIA.

INTERNAL-COMBUSTION ENGINE.

No. 876,472.

Specification of Letters Patent.

Patented Jan. 14, 1908.

Application filed September 4, 1906. Serial No. 333,237.

To all whom it may concern:

Be it known that we, HARRY A. MILLER and FRANK M. ADAMSON, both citizens of the United States, residing at Pasadena, in the county of Los Angeles and State of California, have invented new and useful Improvements in Internal-Combustion Engines, of which the following is a specification.

This invention relates to internal combustion engines and particularly to the two cycle type wherein the ports are opened and closed by the piston. In such engines, during the up stroke, a partial vacuum is formed in the compression or crank chamber and a back pressure exists at the exhaust port and as the exhaust port in the cylinder is usually arranged substantially opposite the intake port, there is a movement of gas across the cylinder, around each side of the piston from the exhaust port to the intake port, which retards and restricts the exhaust of spent gas, and reduces the vacuum in the compression chamber, and impoverishes the unignited gas in quantity by reducing the vacuum, and also in quality by the admixture therewith of the retained spent gas, thus reducing the power of the engine and reducing economy. The main object of the invention is to eliminate these disadvantages.

Referring to the accompanying drawings:— Figure 1 is a vertical section through one form of two cycle engine embodying the invention; such details of the engine as are unnecessary to an understanding of the invention being omitted. Fig. 2 is a vertical section through the piston. Fig. 3 is a transverse section on line x^3-x^3 of Fig. 1. Fig. 4 is a vertical section through the piston showing another form of the invention.

The cylinder 1 of the engine is provided with exhaust port 2 and inlet port 3 which are about in line on opposite sides of the cylinder. The cylinder has a by-pass 4 communicating with the port 3. The piston 5 is a trunk piston and has a by-pass port 6 formed in its side wall and arranged to register with by-pass 4 when the piston is at or near the bottom of its stroke.

When the piston is at the bottom the compressed gas in the compression chamber, guided by a curved baffle plate 7 formed in the piston, rushes through port 6 into by-pass 4 and issues through port 3 into the cylinder,

being deflected by a deflector 8, and drives out the spent gas through port 2. As the piston moves up it closes ports 2 and 3 and by-pass 4 and compresses the gas for ignition, the piston being provided as usual with piston rings 9.

When the piston is in its upper position its lower edge opens a supply port 5 which is thus given direct communication with the lower portion of the cylinder and the crank case, and the partial vacuum which has been produced in the crank chamber and lower part of the cylinder during the upward movement of the piston causes the fresh fuel to rush in through port 5 into the lower part of the cylinder and the crank case. This fuel which has thus entered is compressed when the piston moves down and is admitted through the piston to the cylinder above the piston as before described.

In order to prevent the transverse movement of gas referred to, both sides of the piston have longitudinal recesses 10 which receive plates 11 which are firmly pressed against the cylinder walls by a coil spring 12 arranged in the hollow crank pin 13. These plates slide up and down with the piston, and having close contact with cylinder walls between exhaust port 2 and inlet port 3, shut off communication around the sides of the piston between these two ports and prevent the lateral movement of gas from the exhaust port to the inlet port. These plates are located on a line at right angles to a line between the inlet and exhaust ports. Heretofore these two ports have been extended over a less arc of cylinder wall than desirable in order to increase the circular distance between them to minimize the transverse leakage referred to; and it is obvious that with this invention the arc of the ports can be increased to the desired point for quickness of opening and closing as the transverse leakage is prevented.

If desired the plates 11 can be pressed out by flat springs 14 as shown in Fig. 4.

What we claim is:—

1. A cylinder, a piston therein, the cylinder having inlet and exhaust ports in opposite sides thereof which are opened and closed by the piston, plates carried by the piston and extending longitudinally thereof, said plates having their entire area of wearing

100

105

surface continuously in sliding contact with the cylinder, the plates having paths of movement out of line with the inlet and exhaust ports for preventing circumferential leakage between the inlet and exhaust ports.

2. A cylinder, a piston therein, the cylinder having inlet and exhaust ports in opposite sides thereof which are opened and closed by the piston, and means between the piston and cylinder at diametrically opposite points of the piston, and on a line at right angles to a line between the inlet and exhaust ports, for preventing leakage between the inlet and exhaust ports circumferentially of the piston.

3. A cylinder, a trunk piston therein, the cylinder having inlet and exhaust ports which are opened and closed by the piston and having a by-pass port, the piston having a port which periodically registers with the by-pass port, and means free from all said ports between the piston and cylinder for preventing lateral leakage circumferentially of the piston between said inlet and exhaust ports.

4. A cylinder, a piston therein, the cylinder having inlet and exhaust ports which are opened and closed by the piston, the piston having longitudinal recesses, plates in said recesses, and a coil spring extending through the piston and bearing against the plates to hold them against the cylinder.

5. A cylinder, a piston therein, a hollow wrist pin in the piston, the cylinder having inlet and exhaust ports which are opened and closed by the piston, the piston having longitudinal recesses, plates in said recesses, and a coil spring in the wrist pin and extending through the piston walls and bearing against the plates to hold them against the cylinder.

In testimony whereof, we have hereunto set our hands at Los Angeles California this 21st day of August 1906.

HARRY A. MILLER.
FRANK M. ADAMSON.

In presence of—

GEORGE T. HACKLEY,
FRANK L. A. GRAHAM.
